Primary Examiner — Cathron Brooks*Assistant Examiner* — Christian P McLean(74) *Attorney, Agent, or Firm* — Reising Ethington P.C.(57) **CLAIM**

The ornamental design for a vehicle front fascia, as shown and described.

DESCRIPTION

FIG. 1 is a perspective view of the vehicle front fascia; FIG. 2 is a front view thereof;

FIG. 3 is left side elevation view thereof (where the right side elevation view is omitted since the right side elevation view is identical to the left side elevation view); and, FIG. 4 is a top plan view thereof.

The broken lines shown in the drawings depict portions of the vehicle front fascia that form no part of the claimed design.
